UNITED STATES PATENT OFFICE.

OSBORNE C. CASSELL, OF WINCHESTER, VIRGINIA, ASSIGNOR TO CROMPTON & KNOWLES LOOM WORKS, OF WORCESTER, MASSACHUSETTS, A CORPORATION OF MASSACHUSETTS.

PROTECTOR MECHANISM FOR LOOMS.

Application filed May 21, 1923. Serial No. 640,346.

To all whom it may concern:

Be it known that I, OSBORNE C. CASSELL, a citizen of the United States, residing at Winchester, in the county of Frederick and 5 State of Virginia, have invented a new and useful Protector Mechanism for Looms, of which the following is a specification.

This invention relates to protector mechanism for looms and more particularly to 10 devices to stop the loom should the protector become inoperative because of a broken protector spring.

Protector mechanisms are used to stop the loom should the active shuttle fail to box 15 properly and as usually constructed employ a protector rod having a dagger to engage knock-off mechanism and fingers to engage the binders associated with the boxes on the ends of the lay. A coiled spring ordinarily 20 surrounds the rod and normally holds the dagger up in knock-off position until the shuttle enters one of the boxes, at which time the binder and finger are actuated so as to move the dagger out of knock-off position. 25 Occasionally the spring breaks and the dagger falls of its own weight to a position to clear the knock-off mechanism. Obviously should a shuttle fail to box under these conditions 30 the loom will continue to operate and a warp smash will result.

It is the principal object of my invention to provide means to stop the loom when the protector rod spring breaks and the devices to accomplish this result may comprise an arm on the shipper handle and a dog on the lay held out of the path of the arm until the spring breaks, at which time the dog will fall into the path of the arm and rock 40 the shipper rod to stop the loom.

With these and other objects in view which will appear as the description proceeds my invention resides in the combination and arrangement of parts hereinafter described 45 and claimed.

In the drawings—

Fig. 1 is a front elevation of a loom embodying my invention,

Fig. 2 is an end view looking in the direction of arrow 2 in Fig. 1,

Fig. 3 is an enlarged fragmentary top plan looking in the direction of arrow 3 in Fig. 1, showing parts of the invention,

Fig. 4 is a vertical section taken on line 4—4 of Fig. 3, and 55
Fig. 5 is a vertical section taken on line 5—5 of Fig. 4.

In the drawings, there is shown a loom having loomsides 10, a breast beam 11, lay 12, shipper rod 13 and shipper handle 14. 60 A lever 15 pivoted at 16 is connected at its lower end to a rod 17 and has a pin and slot connection with the shipper handle. A protector rod 18 is mounted in bearings 19 on the lay and has rigid therewith binder 65 fingers 20 (one of which is shown in Fig. 2) and a dagger 21. A lever 22 pivoted at 22' to the under side of the breast beam has one end extending in front of the shipper handle and the other end placed in the path 70 of the dagger when the latter is in raised position. The parts are so arranged that the shipper handle is moved in a clockwise direction as viewed in Fig. 2 when it is 75 desired to stop the loom.

A coiled spring 23 surrounds the protector rod and has one end straightened and projecting under the lay as at 24 in Figs. 3 and 5. The other end of the spring is held in a collar 25 adjustably set on the rod 18 80 and in this way each finger 20 is held against its binder 26, and dagger 21 is held in knock-off position. When a shuttle is properly boxed the binder 26 is pushed out to move the dagger 21 down out of the path of lever 85 22 as the lay moves forward. When the shuttle fails to box the spring holds the dagger 21 in raised position and as the lay advances the lever 22 is swung on its pivot to move the shipper handle to knock-off position. All the parts thus far described are 90 of the ordinary construction and operate in the usual manner.

My improvements include a dog 27 pivoted to the lay at 28 and provided with a hook 95 which extends over the end 24 of the spring and serves to hold the dog in the full line position shown in Figs. 1 and 4. So long as the spring 23 is intact the dog is held to one side but should the spring break or the 100 collar 25 work loose on the protector rod, the spring rotates on the rod and the end 24 moves out of supporting position and the dog falls to the lowered position indicated in dotted lines in Fig. 4. When in 105 this position the lower end of the dog en-

gages an arm 30 clamped on the shipper rod 13 and as the lay advances the shipper rod is rocked in a clockwise direction to knock off the loom.

5 The lower end of arm 30 is cam shaped to ease the motion communicated to the shipper shaft and the arm is adjustably set on the shaft by screws 31 so that its position can be varied with respect to dog 27.

10 From the foregoing it is apparent that my improvements are extremely simple and are effective to stop the loom as soon as a fault develops in the coiled spring or its collar.

15 Having thus described my invention, it will be evident that changes and modifications may be made by those skilled in the art without departing from the spirit and scope of the invention as set forth in the 20 claims, and I do not wish to be otherwise limited to the details herein disclosed, but what I claim is:

25 1. In a loom having shipper mechanism, a lay, a protector rod and dagger thereon, and a spring to hold said dagger in knock-off position, the combination of cooperating 30 elements associated with the lay and shipper mechanism, said elements being held in inoperative position so long as the spring is effective to hold the protector dagger in knock-off position, but being released to

move to operative position to stop the loom when the spring becomes defective and incapable of holding the dagger in knock-off 35 position.

2. In a loom having a lay, a protector rod and dagger thereon controlled by the shuttle, shipping mechanism and a spring to hold the protector dagger in knock-off position, the combination of a dog on the lay normally held inoperative by the spring but free to assume an operative position when the spring becomes inoperative to hold the protector dagger in knock-off position, and means associated with the shipper mechanism to stop the loom when the dog assumes 40 said operative position.

3. In a loom having shipper mechanism, a lay, a protector rod and dagger thereon and a spring normally holding the dagger in knock-off position, the combination of an arm connected to the shipper mechanism, and means moving with the lay and normally held out of the path of the arm by the spring so long as the latter is intact, but 50 said means being arranged on the failure of said spring to hold the dagger in knock-off position to engage said arm and stop the loom.

55 In testimony whereof I have hereunto affixed my signature.

OSBORNE C. CASSELL.
